UNITED STATES PATENT OFFICE.

PATRICK CUNNINGHAM, OF NEW BEDFORD, MASSACHUSETTS.

MACHINE FOR MINCING WHALE-BLUBBER.

SPECIFICATION forming part of Letters Patent No. 232,691, dated September 28, 1880.

Application filed October 31, 1879.

To all whom it may concern:

Be it known that I, PATRICK CUNNINGHAM, of New Bedford, county of Bristol, and State of Massachusetts, have invented a new and useful Improvement in Machines for Mincing Whale-Blubber, of which the following is a specification.

The object of my invention is to enable the work of mincing whale-blubber to be performed with less labor and with a considerable saving of oil, the manner of attaining this end being more fully hereinafter explained.

The accompanying drawing is a view, in perspective, of my invention.

15 In the drawing, A is the frame of the machine, on the top of which is placed the shaft O, which shaft is furnished with the crank O' and the bevel-gears E' and g. At right angles with the shaft O is placed the shaft B', which 20 is furnished with the balance-wheel A', the knife B, and the bevel-gear h, which gear meshes with the bevel-gear g on the shaft O, so that when the crank O' is turned the knife B is caused to revolve. To the frame A is 25 also hung the shaft E, which shaft is furnished with the worm-gear d and the bevel-gear d', which bevel-gear meshes with the bevel-gear E', by which means motion is imparted to the shaft E.

30 The box or trough C is attached to the frame A at right angles with the face of the knife B, and in such a manner as to be adjustable vertically.

To the under side of the box C are hung the 35 shafts a'', b'', c'', and k''. The shaft a'' is furnished with the spur-gear a', the gear a, and a chain-wheel, (which is not shown in the drawing,) which chain-wheel occupies a position in the center of the shaft a'', between its bearings, 40 as will more fully appear hereinafter.

The shaft b' is furnished with the loose pinion b and a pulley, the same as is shown at n'.

Around the chain-pulley on the shaft a'', before described, and the pulley attached to the 45 shaft b', is placed an endless chain of lags, which lags are furnished with spurs, as shown at c'. This lag-chain is adjusted to the bottom of the box C in such a manner that the spurs project a short distance through the 50 slots, which are made longitudinally in the metallic bottom of the box C, as shown at n.

The shafts c'' and k'' are duplicates of and are furnished in all respects the same as the shafts a'' and b', with the exception of the loose pinion b, this pinion being for the purpose of 55 imparting motion from the first pair of shafts, a'' and b' to the second or duplicate pair, c'' and k''. These two pairs of shafts and their furnishings, just described, constitute the feed of the machine, motion being imparted to the feed by 60 means of the worm-gear d acting upon the spur-gear a', thus producing a continuous and steady motion to the feed. The sides of the box C are cut nearly through, as shown at m, so as to allow the knife B to revolve freely. 65 The knife B has a volute edge and the blade is spirally arranged upon its shaft, where it is held in position by the spiral-faced collars i i', which are secured against its opposite sides.

The operation of the machine is as follows: 70 A piece of blubber is placed in box C, and the crank being turned the blubber is carried forward to the knife by the operation of the feed, when that part of the knife l' commences to cut, and as the knife revolves the cut is finished by the part of the knife-edge l'', thus obtaining the easiest cut possible—viz., a long drawing stroke.

It will be observed that the knife B makes a complete revolution at each cut, and the whole 80 length of the knife-edge passes through the blubber laterally, while the vertical cut, on account of the spiral shape of the knife, is only about one-eighth of said length of the knife-edge.

85 Whale-blubber is of a spongy nature, and in order to slice it in pieces of uniform thickness it is necessary to have about the above-mentioned proportion of drawing stroke to vertical cut. It is also necessary that the slices should 90 be of uniform thickness in order that the oil may render properly.

The knife is made to take a spiral or screw form on its shaft, so that the edge of the knife in making the cut may follow the motion of 95 the feed, thus preventing the crowding of the blubber against the knife.

I am aware that knives have been placed spirally on the shaft, in order that the knife-edge may advance in even speed with the material cut; but I do not claim anything in 100 this regard.

I am aware that mincing-machines have been provided with broad flat spiral-edged knives, as in the patents of J. D. Hall, dated February 14, 1865, and numbered 46,350, and W. Vine, 5 granted May 10, 1859, and numbered 23,966; and I do not claim said knives or anything shown in said patents.

I am also aware that the revolving knives and a spur-feed chain of a mincing-machine 10 have been operated by intermediate gear-connection with a common prime mover, as in the patent of Cluney & Lepine, dated April 14, 1874, and numbered 149,640, and do not claim this construction broadly.

Having thus described my invention, what 15 I claim, and desire to secure by Letters Patent, is—

1. In a machine for mincing whale-blubber, the combination, with the feed-box C, having 20 the slots *m* in its sides and the longitudinal slots *n* in its bottom, of the knife B, having the spiral or volute edge arranged to play transversely through said feed-box and slots *m*, the feed-chain provided with spurs projecting through said slots *n*, and a common

prime mover connected by intermediate mechanism with said knife and chain, substantially as described.

2. In a machine for mincing whale-blubber, the combination, with a feed-box and a traveling feed-chain provided with spurs projecting through longitudinal slots in the bottom of said box, of a knife formed of a smooth plate, continuous from center to periphery and having a spiral or volute edge playing transversely 30 through said feed-box, substantially as described.

3. In a machine for mincing whale-blubber, the combination of the shaft B', carrying the bevel-wheel *h* and volute knife B, the shaft O, 40 carrying the bevel-wheels *g* and E' and crank O', the shaft E, carrying worm *d*, and the feed-chain provided with spurs and operated by intermediate gear-connection with said worm *d*, substantially as described.

PATRICK CUNNINGHAM.
